UNITED STATES PATENT OFFICE

136,266

DESIGN FOR A LAMP SHADE

William Hansen, Chicago, Ill.

Application May 15, 1942, Serial No. 106,912

Term of patent 3½ years

To all whom it may concern:

Be it known that I, William Hansen, a citizen of the United States, residing at Chicago, in the county of Cook and State of Illinois, have invented a new, original, and ornamental Design for a Lamp Shade, of which the following is a specification, reference being had to the accompanying drawing, forming a part thereof.

Fig. 2 is a broken side elevational view thereof;
Fig. 3 is a top plan view of the shade.
The sides of the shade not shown in elevation correspond to the sides shown in Figs. 1 and 2.

I claim:

The ornamental design for a lamp shade, substantially as shown and described.

WILLIAM HANSEN.
